UNITED STATES PATENT OFFICE

WILLIAM F. HELMOND, OF WEST HARTFORD, CONNECTICUT, ASSIGNOR TO UNDERWOOD ELLIOTT FISHER COMPANY, OF NEW YORK, N. Y., A CORPORATION OF DELAWARE

TYPEWRITING MACHINE

Application filed June 26, 1929. Serial No. 373,731.

This invention relates to a step-by-step carriage-feeding mechanism of typewriting machines.

In the Underwood machine, the universal bar is actuatable by any type-bar and forms part of a train whose movement effects the vibration of the carriage-feeding dogs. The type-bars are pivoted in the arc of a circle. The universal bar is curved accordingly; and 10 the universal-bar frame resembles a parallel motion linkage. The carriage-feeding cycle of the stepping dogs occurs at the end of the printing stroke of the type-bar, and at the beginning of its return stroke, and extreme 15 accuracy of operation of said feeding dogs and of the universal-bar frame is necessary, and especially that the universal-bar frame shall be given uniform movements by all of 20 the type-bars. To secure this uniformity of movement is found difficult, owing to the fact that said frame is large, and that the universal bar is lengthy, and the entire structure has to be made very light, so as to secure speed of 25 operation. The difficulty arises from weakness, due to the lightness.

It is therefore found necessary in finishing up a machine in the factory, and finally in inspecting the same before its delivery to customer, to give the universal-bar mechanism severe tests, and sometimes it becomes necessary to true up the universal-bar frame by bending it. There has also been adopted means for adjusting either end of the universal-bar frame, forwardly or backwardly, to 30 true it with the type-bars. This bending and adjustment is difficult, because the universal-bar frame is hemmed in at the front by the type-bars, at the rear by the escapement-mechanism, at the bottom by the key-levers, at the top by the carriage and at the sides by various other moving parts of the machine, and the universal-bar mechanism is intermingled with the escapement-mechanism.

To gain access to the universal-bar frame, 45 it has been necessary oftentimes to remove the escapement-wheel and also the dog-rocker, thereby disturbing their adjustments, and also disturbing certain adjustments of the universal-bar mechanism. These various 50 parts may have to be removed, replaced and

readjusted several times before the machine reaches the customer, and in consequence it is apt to develop faults when put into use at high speed.

One of the objects of the invention is to 55 reorganize the universal-bar mechanism and also the parts controlled thereby, with a view to overcoming the above-mentioned and other difficulties. By the invention an advantage is secured in the reorganization of the universal-bar frame and its supports to form an 60 entirely separate unit or department in the machine, apart from the dog-rocker and the escapement-mechanism, and also in the separate reorganization of the dog-rocker and 65 escapement-wheel mechanism to form a separate cluster of parts.

A further feature is the reorganization of 70 the escapement-wheel and dog-rocker mechanism as a separately made and assembled unit, having its own separate skeleton or frame, and providing for ready attachment of said escapement-unit to the machine and detachment of the same from the machine independently of the universal-bar mechanism, 75 thus affording ready access to the latter from the rear, without the necessity of disturbing any adjustment of any part of the escapement-wheel unit, or the adjustment of any 80 part of the universal-bar unit.

The frame of the escapement-unit is in the 85 form of a bracket, which is given a broad bearing on the mount to which it is attached, and four well-separated screws are used for fastening said escapement upon said mount, whereby the escapement-unit can be brought mechanically to the exact position required for co-operation with the escapement-rack of the typewriter-carriage.

The universal-bar mechanism is reorganized as a separate unit which may be manufactured and its parts assembled and inserted bodily in the machine. This universal-bar unit has its own separate frame 90 which has a broad base, and is given broad support upon the main framing of the typewriter. Said bracket includes posts or standards which form the mount upon which the escapement-wheel unit is fastened. The 95 escapement-bracket is provided with a front 100

vertical face, which is fastened to the rear of its mount on the universal-frame bracket; and the escapement-wheel frame is afforded room for vertical movement when inserting 5 it into the machine and bringing it to its place upon said post. The escapement-wheel bracket may first be removed, and the universal-bar unit may then be loosened from the machine-frame and drawn back 10 out of the machine. No adjustment is disturbed when removing either the escapement-wheel unit or the universal-bar unit.

In an Underwood machine it is the practice to use a cone-headed screw to form an 15 adjustable stop for the loose dog of the carriage-escapement. In the reorganization of the escapement-mechanism, this screw is discarded, and there is substituted for it a rod which is threaded into one of the side bars 20 of the escapement-wheel unit, and has a cone-point for use with the feeding dog, and is firmly secured by a nut.

Another feature of the invention is the 25 improved manner of mounting the escapement-wheel upon the bracket, securing compactness, which is needed in order to permit the escapement-wheel to be withdrawn downwardly from the machine within the 30 space which is afforded by other parts of the typewriter-mechanism.

Another feature of the invention is to 35 make the universal-bar mechanism light and compact, with a view to improving the touch upon the type-keys; and one feature is the use of two springs, one for each side of the universal-bar frame, each spring being adjustable independently, thereby securing sensitiveness and accuracy of operation of the universal bar.

40 The universal-bar frame is made of a casting of duralumin or aluminum, and is fitted with hardened steel bushings for bearings, to secure extreme lightness, quickness and accuracy of operation.

45 Other features of the improvement relate to the space-key, which operates the carriage-feeding dogs without moving the usual ink-ribbon in any way, while provision is made for ready disconnection of the space- 50 key train from the escapement-wheel unit when it is desired to remove said unit from the machine.

Other features and advantages will hereinafter appear.

55 In the accompanying drawings,

Figure 1 is a sectional side elevation showing the invention of the novel escapement-mechanism unit removably attached to a novel supporting frame provided in the 60 typewriter machine, and showing the dog-rocker in its operated position.

Figure 2 is a central sectional side elevation of an Underwood typewriting machine having the present improvements incorporated therein.

Figure 3 is a part-sectional plan of an improved universal-bar mechanism.

Figure 4 is a rear elevation of the upper part of the escapement-mechanism unit.

Figure 5 is a perspective view of certain 70 of the present improvements, showing the novel escapement-mechanism unit separated from the novel supporting frame.

Figure 6 is a sectional elevation of rocker or connected swinging guide-arms upon 75 which the universal bar is pivotally supported at its rear.

Figure 7 is a perspective view to illustrate the means for truing the universal bar by adjusting forwardly or backwardly one of the 80 gudgeons of the universal bar guiding frame seen at Figure 6.

Figure 8 is a perspective of a novel supporting frame for the universal-bar mechanism, forming therewith a detachable unit 85 which is mounted in the main frame of the typewriter; this detachable supporting frame including a pair of standards, to which is attachable the escapement-mechanism unit seen at Figure 5.

The carriage 10 of the typewriting machine runs upon guide-rails, of which one is seen at 11, and is driven by a spring-barrel 12, and carries a frame 13 in which is journaled a platen 14; said platen-frame 13 running upon a shift rail forming part of a frame 15 which is shiftable up and down and includes a rock-shaft 16.

Type-bars 17 are pivoted at 18 upon a 100 transverse vertical segment 19, to swing against the platen 14. The type-bars are operated by keys 20 upon levers 21, which are fulcrumed upon a horizontal transverse rod 22, and provided with returning springs 23, said rod 22 being mounted in the base 24 105 of the typewriting machine, said base including rear wall 25. The key-levers 21 are connected to the type-bars by means of a system of bell-cranks 26, pivoted upon a fulcrum-rod 27, which is carried by a transverse stiffening bar 28 joining the sides of the base 24. As so far described, the parts are in common use in Underwood typewriting machines.

The shoulders 29 of the type-bars strike 115 vertically against a crescent-shaped universal bar 30, arranged at the back of the segment 19 and suitably guided for backward parallel movement, so that it may be operated the same by all the type-bars. This universal bar forms part of a reciprocating frame of which another main member is in the form of a skeleton plate, table or body 31, which is rigidly secured to the universal bar 30 by means of side ears 32, which may be bent down from the plate and riveted to the universal bar 30. This universal-bar plate 31 is provided at its rear with ears 33, whereby it is pivoted at 34 to the upper ends 120 of a pair of rocking arms 35, 36, which are 125 130

integral with a transverse rock-shaft 37, from which they rise for the purpose of guiding the universal bar 30 and the frame 31. The front guide for the universal-bar frame 5 is in the form of a tongue 38, which is fitted to slide in a guide-bearing 39 in the wall of segment 19.

One of the main functions of the universal bar is performed by means of an ear or abutment 40 which is bent down at the rear end thereof, to serve as a tappet, striking against a projection 41 that is provided upon a rocker 42, having a detent-dog 43 and a feeding dog 44, both dogs adapted to mesh with the teeth of an escapement-wheel 45, which is driven by a pinion 46, the latter being in mesh with a rack 47 which is hung in the usual manner upon the typewriter-carriage 10; whereby at the operation of the keys 20, the spring-barrel 12 is permitted to advance the carriage step by step under the control of the escapement-dogs 43, 44.

For supporting the universal-bar mechanism as an entirety, there is provided in the typewriting machine a novel detachable internal frame, including base-portion 48 and standards 49, 50 rising from opposite sides thereof. One of the uses of said standards 30 is to carry spreading arms 51, having upon their outer ends bosses 52, to carry the journals of the rocking frame 35, 36, 37. The base 48 is detachably fastened down upon the rear wall 25 of the typewriter-base by means of screws 53. Said base 48 extends forwardly to rest upon separated bearings 54 that are cast upon the cross-bar 28 of the framework; the front of the base 48 being detachably secured by screws 55 upon said bearings 54, thereby increasing the stiffness 40 of the typewriter-framework, and providing a rigid support for the universal-bar mechanism and other carriage-feeding parts presently to be described in detail.

The frame 48, 49, 50 taken with the rocker 35, 36, 37 and the universal-bar frame 31 and appurtenances form a manufacturing assemblage which may be fabricated as a unit and then inserted bodily in the typewriting machine, with the guiding tongue 38 inserted 50 in the guide-hole 39 in the type-bar segment. Then the unit may be fastened in place by the screws 53, 55.

This unit, it will be seen, may include returning springs 56 for the universal bar. At their rear ends the springs are caught upon projecting shanks 57 of pivot-screws 34, which join the universal-bar frame to the rocking frame 35, 36, 37. At their forward 60 ends the springs are caught upon bends 58 which project from the forward ends of rods 59, whose rear ends are rigidly mounted in bosses 60. The tension of each spring 56 may be regulated independently of the other spring, by adjusting its rod 59 forwardly or backwardly within its bearing 60, and then

fastening the rod by set-screw 61. These springs occupy positions nearly at the extreme sides of the universal-bar frame, and the adjustment of one spring independently of the other makes it practicable to secure 70 easy, accurate and sensitive operation of the universal-bar frame. The spring-bosses 60 are secured upon the ends of plates 62, which are attached by screws 63 to the front faces of the standards 49 and 50.

The right-hand plate 62 is provided with a stop-arm 64, which occupies a position in front of said lug 40 that is bent down from the rear of the universal-bar frame 31. Lug 40 is normally held against the stop-arm 64 by means of said returning springs 56. The stop-arm 64 is of substantial length, to render it capable of being bent forwardly or backwardly for the purpose of adjusting the normal position of the universal bar, to aid in securing sensitiveness and accuracy at high speed of operation. The lug 40 thus serves as a stop, as well as a tappet for striking the projection 41 on the dog-rocker to operate the same.

The universal-bar frame must vibrate at high speed and must therefore be very light, as well as accurate in operation, and necessarily it is made an object of considerable attention, both when manufacturing the machine and subsequently in repairing and adjusting the same. The universal-bar frame, however, has been fabricated and assembled as a permanent portion of the machine, and has been rendered inaccessible by reason of 100 its confined position under the typewriter-carriage and between the typewriter-segment and the carriage-escapement mechanism and over the key-lever system. Considerable advantage therefore is derived from the present invention in combining the universal-bar frame and its appurtenances into a manufacturing assemblage or unit with its supporting frame, and permitting the entire unit to be withdrawn from the back of the machine 105 for inspection and adjustment.

One of the principal difficulties with this very light and rambling universal-bar frame, is that the long curved universal bar 30 is apt to get out of parallel with the system 115 of type-bar shoulders or "heels" 29; the universal bar being found perhaps to set too far back at one end and too far forward at the other end, so that it is operated unequally by different type-bars, with corresponding inequality in the vibrations of the escapement-dog rocker and ribbon-vibrator. Adjustment of the universal bar to overcome the trouble is readily effected by mounting either end of the rocker-frame 35, 36, 37 upon 120 a stud 65, Figures 6 and 7, which extends from an eccentric 66 journaled in the left-hand bearing 52, Figure 3. The eccentric has a head 67, provided with a screw-driver nick 68, so that it may be rotated, thereby 125

shifting the stud or trunnion 65 a little forward or backward, so as to true the universal bar 30 with reference to the system of type-bars. After such adjustment is effected, the 5 stop-arm 64 may be bent a trifle forwardly or backwardly accordingly, to correct the normal position of the universal-bar frame. The head 67 of the eccentric may be provided with notches 69, into any one of which 10 may be set a pin 70 for locking the adjusted trunnion, said pin being inserted in the end of the bearing 52.

The movements of the universal-bar rocker 35, 36, 37 are rendered sensitive and accurate 15 by means of bearings which include sets of balls 71 running in races that are formed in heads 72 of bushings 73 which are forced into the ends of the rock-shaft 37. The stud 65 is cone-pointed to co-operate with its set 20 of balls, and a cone-point 74 is provided for the other set of balls. The point 74 is formed upon a screw-stud 75, which is threaded for longitudinal adjustment, to take up play of the rocker in both bearings; the screw 75 being secured by means of a set-screw 76. The balls may be retained by means of elastic-metal retaining rings 77 that are inserted in interior grooves 78 formed in the heads 72 of the bushings; said rings being split to permit 30 them to be inserted in the open heads of the bushings, and to snap into the grooves. The openings in the bushing-heads 72 are cupped at 79 to form races for the balls.

The eccentric 66 may have a tight fit in 35 the bearing 52, so that it will not be liable to rotate or slip accidentally in said bearing; and it may be fastened by a set-screw 80, Figure 5, at any point to which it may be adjusted. The bushings 73 are made of steel, 40 and are driven into their seats 81 in the rocking frame, the latter being cast of aluminum or duralumin for lightness. At their upper ends the rock-arms 35, 36 may be provided with steel bushings 82, perforated axially to 45 receive pivot-pins 34, the latter having said threaded shanks or extensions 57. In other words, said pivot-pins have the form of bolts, each bolt passing through an ear 84, which is bent down from the universal-bar frame, 50 and being passed through a companion ear 83, the bushing 82 occupying a position between said ears, and the bolt being secured by a nut 86.

It will be seen that all of the foregoing 55 universal-bar mechanism and appurtenances are assembled upon the internal frame 48—50, and may after assemblage be inserted bodily therewith in the machine. The forwardly-projecting tongue 38 fits in the horizontal guide-slot 39 in the segment, Figure 3, and at its opposite side edges is guided by hardened steel pins 87, which are forced into perforations 88 formed in the segment-wall 19. These pins may be in the form of 60 short bushings, avoiding wear and conducting

to easy movement of the universal bar. The tongue is cut out at 89 within the hole or guide-slot 39, to give clearance, and avoid liability of binding, and also to aid in keeping 70 the slot clean.

The usual ribbon-vibrator arm 90 is seen at Figures 3 and 5, for carrying a ribbon-vibrator 91 up and down; said universal-bar plate being slotted at 92 to afford clearance for said arm 90. The cutaway 89 also affords 75 access to the joint between the arm 90 and the vibrator 91.

From the foregoing it will be understood that, after securing the usual ribbon-vibrating bracket 144 upon the universal-bar frame 31, the entire structure, including the universal-bar frame, the rocking frame 35, 36, 37, the springs 56, etc., may be inserted as a unit into the machine, and detachably secured by the screws 53 and 55; whereupon the ribbon-winding mechanism may be attached (by means of a screw 93) to an arm 94, which extends from the rock-shaft 37. Said ribbon-winding mechanism includes a link 95 which is pendent from said screw 93, and is pivoted at its lower end to an arm 96, which extends rearwardly from a horizontal transverse rock-shaft 97. This rock-shaft may be mounted at its left-hand end in a bearing 98 formed upon the base 48 of the universal-bar unit. At its other end, the rock-shaft 97 is mounted in a bearing 99, which is removably attached to cross-bar 28 and corresponds to the bearing heretofore usually provided upon said transverse bar 28. This rock-shaft 97 is therefore actuated at every type-bar stroke, and is employed for driving the usual pawl (not shown) for winding the ribbon-spools (not shown). Said shaft 97 may be loosened and withdrawn from bearing 98 preparatory to withdrawal of bracket 48 from the machine. The bearing 99 is not upon bracket 48. Or the rock-shaft 97 may be taken off together with the bracket 48, after the bracket 99 has been disconnected 105 from 28.

The universal-bar mechanism is thus rendered compact, and the moving parts lightened and simplified, and the cost of manufacture reduced; while said mechanism is 110 rendered easy of access for cleaning and repair and replacement of worn or injured parts.

There now remains to be described the carriage-escapement unit, which includes a detachable frame whereon are mounted the escapement-wheel 45 and the escapement dog-rocker 42. One of the advantages of the invention is that this escapement-unit may be removed alone, without disturbing its adjustments, thus giving access to the universal-bar unit already described, for inspection and cleaning and repair, or for removing the universal-bar unit bodily from the machine. 115

One of the uses of the posts 50 which rise 120

from the base 48 of the universal-bar unit, is to provide supporting means to which the escapement-unit can be detachably secured. The escapement-unit for this purpose includes an open frame (Figure 5), and its side members 100 are fitted back against the rear faces of the posts 50, where they are held by removable screws 101.

10 The escapement-wheel 45 and the pinion 46 are mounted in the top member 102 which joins said side members 100; and a bottom cross-bar 103 joins the lower ends of said side members 100, thus forming a stiff open frame.

15 The pinion 46 may have the one-way connection to the escapement-wheel 45 which is usual in Underwood machines, and is shown in Patent 1,411,024, granted to me March 28, 1922.

20 The escapement-wheel is provided with a hub 104, which extends within a stationary bushing 105, that is inserted in a boss 106 formed upon the top cross-bar or portion 102 of the escapement-wheel frame. This bushing is cupped on its front and rear ends to receive bearing-balls 107. The front circle of bearing-balls runs upon a cone 108 formed at the base of the wheel-hub 104. The rear circle of bearing-balls is retained by a cap 25 in the form of a cupped head 109, which is rigidly secured upon the end of the hub 104 by means of a screw 110.

25 In order to secure a sufficient tightness of the balls in the races, the inner face of the cupped head 109 may be fitted to the end of the wheel-hub 104, by filing off the inner face of the head 109, as required. The bushing 105 is forced into the boss 106. The escapement-wheel and the ratchet-wheel form 30 a unit which is readily mounted upon the escapement-frame before the latter is attached to the typewriting machine.

35 It will be seen that the bearings of the escapement-wheel are made very compact, and especially that they occupy a greatly reduced space in rear of the escapement-wheel 45, to permit the escapement-wheel unit to drop in front of the rock-shaft 16 (of the platen-shifting frame) when it is desired to remove the escapement-frame unit from the typewriter.

40 The detent-dog 43, having the usual beveled working face and normally out of engagement with the escapement-wheel 45, rises from rocker 42, which is supported at its ends upon cone-bearings 112, which are formed upon the inner ends of screws 113, threaded through the opposite vertical arms 45 of the frame of the escapement unit, and secured by set-screws 114. As the shock of arresting the carriage is taken by said rocker 42, the cone-pivots 112 are formed upon the ends of thinned necks 115, which are sufficiently weak to be resilient and capable of 45 yielding under said shocks, thereby reducing

the noise of arresting the carriage 10, and gaining other advantages. These necks are formed between the threaded portions of the screws and the cone-portions, being formed upon the projections which extend towards 50 each other within the frame to carry the rocker 42.

Said rocker 42, as already explained, is operated by lug 40, which is provided upon the universal-bar frame to engage the dog- 55 rocker projection 41, which is threaded for adjustment and is provided with a head, whereby it may be turned for securing earlier or later operation of the dog-rocker. This screw 41 is pinched between the opposite sides of a slotted member 116, formed upon the dog-rocker 42.

When the type-bar is operated and the universal bar is thrust back and the dog-rocker is vibrated, the detent-dog 43 enters a notch 60 in the escapement-wheel 45, while the stepping dog 44 escapes from said wheel, and at this time is vibrated past a tooth of the wheel by means of a draw-spring 117. Said dog 44 has this independent vibration upon a pivot 118 provided upon the dog-rocker 42. The movement of the dog 44 is limited by a cone-stop 119, which is resiliently and inexpensively supported upon the end of a rod 120, the latter being threaded through the upper 65 part of one of the sides 100 of the escapement-frame. The threading permits fine adjustment of the cone-stop, which is secured by a set-screw 121. The cone-carrying rod 120 extends a great distance from the frame-member 100, and is made thin, and possesses much resiliency, whereby the dog is provided with an inexpensive resilient and quiet adjustable stop. It is also noted that the stop is mounted upon a fixture, and therefore does not add 70 weight to the dog-rocker, which it is desired to lighten, since it must vibrate at high speed. The spring 117 causes the dog 44 to slide along the cone-stop 119, the cam serving as a guide to direct the dog 44 back to normal 75 position; this return movement being caused by the pull of the spring 117 upon the dog, said spring extending diagonally for this purpose from an anchorage 122 to a point of connection on the dog 44.

Upon the escapement-frame is also mounted one end of a train of mechanism, whereby the usual space-key 123 may operate the dog-rocker and thereby feed the carriage, without actuating the ribbon either to vibrate it up 80 and down to cover the printing point, or to feed it longitudinally. The space-key 123 therefore does not operate the universal-bar frame 31 (upon which is mounted a part of the ribbon-vibrating train), nor the rock-shaft 97 which winds the ribbon. The space-key 123 may be mounted upon a pair of arms 124, extending forwardly from a rock-shaft 125, having a returning spring 126.

Upwardly from the rock-shaft may extend 85

an arm 127, having at its top a stud 128, whereby it is connected to a link 129, which extends rearwardly, and at its rear end is detachably connected by means of a screw 130 with an adjustable knuckle 131, which is threaded upon the forward end of a horizontal rod or screw 132, which extends rearwardly and is provided at its rear end with a head 133, forming a lug or hook which engages an arm 134 depending from the dog-rocker 42 and integral therewith. When the space-key 123 is depressed, the arm 127 moves forwardly, the link 129 is carried forward, together with the knuckle 131 and the rod 132, and also the lever or head 133, vibrating the arm 134 backwardly to the dotted line position, as at Figure 2, thus effecting rearward movement of the dog-rocker, so that the carriage is fed upon the release of the space-key 123 from pressure. Said stud 128 may have a head, and the link 129 may be provided with a key-hole slot 135 to permit detachment of the forward end of the link. The screw 130 is taken out when it is desired to remove the escapement-wheel unit 102, 103 from the machine. By screwing the operating rod 132 more or less into the knuckle 131, rearward adjustment may be secured between the head 133 and the arm 134 of the dog-rocker, so as to control the timing of the carriage-feed.

The knuckle 131 may be split, and the screw 132 pinched by means of a screw 136. The forward stroke of the arm 134 is limited by an abutment 137, formed upon a screw 138 threaded into a boss 139 upon an arm 140, which projects forwardly from the cross-bar 103 of the escapement-frame. There may thus be determined the point of arrest of the dog-rocker when operated by the space-key.

The head 133 may serve not only as a lug under the control of the space-key 123, but may also serve as a stop for determining the normal position to which the dog-rocker is returned by the spring 117.

Rearward movement of the head 133 from its normal position, Figure 2, is prevented by means of a stop 141 which projects forwardly from the other end of the space-key train beneath a ledge 142 formed upon the front of the typewriter base-frame. If it is desired to vary the normal position of the dog-rocker 42, then the screw 132 may be turned into or out of the head 131, and the adjustment may be secured by screw 136.

The rod 132 is slidably supported in an axial hole 143 provided in the screw 138; and the members 132 and 131 are detached from the machine as part of the escapement-unit, so that it is not necessary to disturb any adjustment in order to remove said unit from the machine. The remaining adjustments upon the escapement-unit are undisturbed in like manner.

In reassembling the unit, the escapement-wheel and upper portion of the unit are passed up behind the rock-shaft 16 of the shift-frame, while the arm 140 and projecting members 132 and 131 are thrust back under the rock-shaft 37 of the universal-bar unit, and the screw 130 is then connected. This provides a satisfactory nesting of the escapement-unit and the universal-bar unit, and produces a compact mechanism of a few small parts, inexpensively made and assembled and placed upon the machine and adjusted.

Variations may be resorted to within the scope of the invention, and portions of the improvements may be used without others.

Having thus described my invention, I claim:

1. In a front-strike typewriting machine having radiating type-bars, the combination with a curved universal bar movable rearwardly by the type-bars, and a carriage-escapement mechanism operable by the universal bar, of a body to the front of which the universal bar is fixed, a guide for the front of said body, a rocking frame to which said body is directly hinged to form its rear guide, said rocking frame being between the carriage-escapement mechanism and the universal bar, said rocking frame being a single stout, torsion-resisting casting of aluminum and including a rock-shaft and arms, the length of said rocking frame approximating the width of the universal bar, bushings of hard metal in the ends of said aluminum rocking frame, opposite supports provided upon the typewriting machine, and trunnions mounted in said supports and extending towards each other to support said rocking frame, said trunnions being relatively adjustable.

2. In a front-strike typewriting machine having radiating type-bars, the combination with a curved universal bar movable rearwardly by the type-bars, and a carriage-escapement mechanism operable by the universal bar, of a body to the front of which the universal bar is fixed, a guide for the front of said body, a rocking frame to which said body is directly hinged to form its rear guide, said rocking frame being between the carriage-escapement mechanism and the universal bar, opposite supports provided upon the typewriting machine, and trunnions mounted in said supports and extending towards each other to support said rocking frame, said trunnions being relatively adjustable, said escapement forming part of a detachable unit, said unit also including carriage-escapement dogs and an escapement-wheel.

3. In a universal-bar mechanism for a typewriter, the combination of a bracket having standards, arms extending from said standards, a rocking frame journaled in said arms, a universal-bar frame hinged to said rocking frame to be guided thereby, plates being attached to said standards, rods extending for

wardly from said plates, returning springs extending from said rods and connected to said rocking frame, said rods being independently adjustable in said plates, and means 5 for securing each rod wherever adjusted, one of said plates having a lengthened arm which serves as a stop against which the universal-bar frame is returned, said arm being bendable forwardly or backwardly for adjusting 10 the normal position of the universal bar.

4. In a front-strike typewriting machine having a platen-carriage and type-bars mounted in a segment below the platen, the combination of a universal-bar system including 15 a frame mounted in rear of said segment to be operated by the type-bars and extending rearwardly from the segment, and also including a rocking frame having a pair of vertical arms whereon the universal-bar 20 frame is pivoted, a bracket forming part of the typewriter-framing at the rear of said universal-bar system and supporting the latter, said bracket having portions forming a mount, a rear vertical bracket removably 25 attached to said mount and forming part of an escapement-wheel unit, said vertical bracket having mounted thereon in rear of said mount a carriage-escapement system including 30 a wheel and a dog-rocker, said dog-rocker having a part engageable by said universal-bar frame for actuation.

5. In a front-strike typewriting machine having a platen-carriage and type-bars mounted in a segment below the platen, the combination with 35 a universal-bar unit including a bracket attached to the main frame of the machine, a pair of rocker-arms mounted on said bracket, and a universal-bar frame guided upon said rocker-arms, said bracket having at its rear portion standards forming 40 a mount, of an escapement-wheel unit detachably secured upon said mount, and including a rotary escapement-wheel mechanism mounted in the upper part of said unit, and also including feed-dogs mounted 45 between the sides of said unit for operation by said universal bar.

6. In a typewriting machine having a platen-carriage, a system of rearwardly-striking type-bars and a segment therefor below the carriage, the combination of a bracket erected upon the framing of the machine below the carriage, having separated 50 posts thereon, bearings provided upon said posts, a rocking frame journaled in said bearings, a universal-bar frame pivoted upon said rocking frame and operated by the type-bars, and an escapement-unit including a 55 frame detachably bolted to the top and bottom of each of said posts, and also including a rotary escapement-mechanism mounted on the upper part of said detachable frame to control said carriage, and a dog-rocker 60 mounted in said detachable frame and oper-

ated by said universal-bar frame to control said escapement-wheel mechanism.

7. In a typewriting machine having a platen-carriage, a system of rearwardly-striking type-bars and a segment therefor below the carriage, the combination of a bracket fastened upon the framework of the machine beneath the carriage and in rear of the type-bars, a universal-bar system mounted upon said bracket, separated posts being provided upon said bracket, and an escapement-wheel unit including a vertical frame detachably bolted to the top and bottom of each of said posts, a rotary escapement-wheel mechanism pivoted on said detachable frame, and a dog-rocker mechanism also mounted on said detachable frame to be operated by said universal-bar mechanism, the universal-bar mechanism being forward of the escapement-wheel mechanism, and said detachable frame, together with the rotary escapement-wheel mechanism and the dog-rocker, forming a unit for separate manufacture and attachment. 75

8. In a typewriting machine having a platen-carriage, a system of rearwardly-striking type-bars and a segment therefor below the carriage, the combination of a universal-bar system including a bracket having separated posts and mounted upon the framework of the machine in rear of the type-bars and below the carriage, and an escapement-unit including a frame and a system of escapement-mechanism mounted thereon, and means for bolting said frame removably to 90 said posts. 95

9. In a typewriting machine, the combination of a power-driven carriage, an escapement-mechanism therefor including an escapement-wheel and a key-operated dog-rocker to control said wheel, cone-pivots for said dog-rocker, shafts upon which said cone-pivots form heads, and means supporting said shafts for endwise adjustment, said cones being joined to said shafts by necks 100 which are substantially thinner than the shafts, for the purpose set forth. 105

10. In a typewriting machine having a platen-carriage and a system of rearwardly-striking type-bars, the combination with a curved universal bar movable rearwardly by the type-bars and a carriage-escapement mechanism operable by the universal bar, of a body to the front of which the universal bar is fixed, a guide for the front of said body, a rocking frame to which said body is directly hinged to form its rear guide, said rocking frame being between the carriage-escapement mechanism and the universal bar, a bracket mounted upon the machine, forward of said escapement-mechanism, and having separated posts, trunnions mounted in said posts and extending towards each other to support said rocking frame, said posts being in rear of the type-bars and below the 115 120 125 130

carriage, an escapement-unit including a frame and a system of escapement-mechanism mounted thereon, said escapement-unit being in rear of said rocking frame, and 5 means for bolting said escapement-unit frame removable to the rear of said posts, said escapement-frame being of open construction and including side members, a transverse bottom member, and a transverse 10 top member, and having a rotary escapement-wheel mechanism journaled in said top member and also having a transverse dog-rocker journaled in said side members, said unit being detachable from the machine independently of said universal-bar rocking 15 frame.

11. In a typewriter-carriage escapement-wheel mechanism, a dog-rocker having a spacing dog, a returning spring connected to 20 said dog to vibrate it to position to enter the next notch in the escapement-wheel, a cone-stop for said dog formed upon the end of a rod, a support from which said rod projects, said rod being adjustable endwise, and means 25 for securing the rod where adjusted.

12. In a typewriting machine, a carriage-escapement unit including a frame, and also including a rotary escapement-mechanism mounted on said frame, and also including a 30 dog-rocker provided with a feeding dog, a returning spring on said unit connected to said dog to vibrate it to position to enter the next notch in the escapement-wheel, and a cone-stop for said dog formed upon the end of a 35 rod, said rod projecting from said frame and being adjustable endwise, and said unit being detachable from the machine without disturbing the adjustment of said stop.

13. A universal-bar unit for a typewriting 40 machine having a broad base for attachment to the main frame of the machine, and having separated rear standards forming a mount for an escapement-wheel unit, a pair of rocker-arms mounted on said base in front of said mount, and a forwardly-extending frame pivoted at its rear to said standards and carrying at its front end a curved universal bar.

14. In a typewriting machine having a letter-feeding carriage, a key-operated universal 50 bar, escapement-mechanism, and ribbon-vibrating mechanism operated by said universal bar, the combination of a space-key, a spring-returned train operated by said space-key, including a rock-shaft whereon said space-key 55 is mounted, an arm extending from said rock-shaft, a link extending from said arm, a knuckle to which the end of the link is detachably connected, a rod upon which said knuckle is threaded, a lug provided upon the 60 opposite end of said rod, a dog-rocker having an arm engaged by said lug to enable the space-key to rock the dog-rocker and feed the carriage, the operating rod being adjustable into the knuckle, and means for securing the 65 rod where adjusted.

15. In a typewriting machine having a letter-feeding carriage, a key-operated universal bar, escapement-mechanism, and ribbon-vibrating mechanism operated by said universal bar, the combination of a space-key, a 70 spring-returned train operated by said space-key, including a rock-shaft whereon said space-key is mounted, an arm extending from said rock-shaft, a link extending from said arm, a knuckle to which the end of the link is detachably connected, a rod upon which said knuckle is threaded, a lug provided upon the 75 opposite end of said rod, a dog-rocker having an arm engaged by said lug to enable the space-key to rock the dog-rocker and feed the carriage, the operating rod being adjustable into the knuckle, means for securing the rod where adjusted, a screw having an abutment serving as an adjustable stop for said dog-rocker arm, said lug being adjustable to determine the normal position of the dog-rocker, and a spring for holding said dog-rocker against said stop, said space-key train having an arresting stop which determines 80 the normal position of said lug.

16. In a typewriting machine having a letter-feeding carriage, a key-operated universal bar, escapement-mechanism, and ribbon-vibrating mechanism operated by said universal bar, the combination of a space-key, a 90 spring-returned train operated by said space-key, including a rock-shaft whereon said space-key is mounted, an arm extending from said rock-shaft, a link extending from said arm, a knuckle to which the end of the link is detachably connected, a rod upon which said knuckle is threaded, a lug provided upon the opposite end of said rod, a dog-rocker having an arm engaged by said lug to enable the space-key to 95 rock the dog-rocker and feed the carriage, the operating rod being adjustable into the knuckle, means for securing the rod where adjusted, said rod slidable axially through a screw which is threaded into a fixture for endwise adjustment to determine the length of stroke of the dog-rocker, the rod being adjustable endwise through said screw to vary the normal positions of the lug and the dog-rocker, and being for this purpose threaded into said knuckle, and means for securing the 100 adjustment of the rod.

17. In a typewriting machine having a letter-feeding carriage, a key-operated universal bar, escapement-mechanism, and ribbon-vibrating mechanism operated by said universal bar, the combination of a space-key, a spring-returned train operated by said space-key, including a rock-shaft whereon said space-key is mounted, an arm extending from said rock-shaft, a link extending from said arm, a knuckle to which the end of the link is detachably connected, a rod upon which said knuckle is threaded, a lug provided upon the opposite end of said rod, a dog-rocker having an arm engaged by said 110 115 120 125 130

Iug to enable the space-key to rock the dog-rocker and feed the carriage, the operating rod being adjustable into the knuckle, means for securing the rod where adjusted, said rod being slideable axially through a screw which is threaded into a fixture for endwise adjustment to determine the length of stroke of the dog-rocker, the rod being adjustable endwise through said screw to vary the normal positions of the lug and the dog-rocker, and being for this purpose threaded into said knuckle, and means for securing the adjustment of the rod, said knuckle, screw and rod forming parts of an escapement-unit which may be detached without disturbing any of the adjustments aforesaid.

18. In a typewriting machine having a carriage and escapement-mechanism therefor, including a dog-rocker and an operating arm pendent from said dog-rocker, and also having a system of key-levers, the combination of a transverse rock-shaft beneath the key-levers, a space-key mounted upon said arms and extending upwardly from said rock-shaft, an upstanding arm on said rock-shaft, a link extending rearwardly from said arm, a fitting upon the rear end of said link, and a slide in the form of a screw threaded into said fitting and having a head to engage the pendent dog-rocker-arm to drive the same.

19. In a typewriting machine having a carriage and escapement-mechanism therefor, including a dog-rocker and an operating arm pendent from said dog-rocker, and also having a system of key-levers, the combination of a transverse rock-shaft beneath the key-levers, a space-key mounted upon said arms and extending upwardly from said rock-shaft, an upstanding arm on said rock-shaft, a link extending rearwardly from said arm, a fitting upon the rear end of said link, and a slide in the form of a screw threaded into said fitting and having a head to engage the pendent dog-rocker arm to drive the same, said slide movable in a mount which is threaded into a portion of the frame-work and is provided with a head to serve as an adjustable stop for said pendent arm.

WILLIAM F. HELMOND.
